UNITED STATES PATENT OFFICE

JAMES B. COREY, OF BRADDOCK, PENNSYLVANIA.

VOTING APPARATUS.

SPECIFICATION forming part of Letters Patent No. 607,503, dated July 19, 1898.

Application filed April 17, 1897. Serial No. 632,566. (No model.)

To all whom it may concern:

Be it known that I, JAMES B. COREY, a citizen of the United States, residing at Brad-
dock, in the county of Allegheny and State
5 of Pennsylvania, have invented or discovered
a new and useful Improvement in Voting Ap-
paratus, of which the following is a full, clear,
and exact description, reference being had to
the accompanying drawings, forming part of
10 this application, in which—

Figure 1 is a front elevation of one of my improved vote-registering machines. Fig. 2 is a central vertical section taken on the line II II of Fig. 1. Fig. 3 is a cross-sectional view 15 taken on the line III III of Fig. 2. Fig. 4 is a similar view on the line IV IV of the same figure. Fig. 5 is a fragmentary piece 20 of the ballot-strip. Fig. 6 is an interior face view of a voting-booth equipped with my machines. Fig. 7 is a side elevation, partly in section, of the booth. Fig. 8 is a perspective detail view of parts of the operative and locking mechanism, showing a modified construction in which the ballot is advanced by the 25 return stroke of the rod. Fig. 9 is a detail view showing the inner end of the rod pro-
vided with the locking-latch and the locking and returning finger in normal position. Fig. 10 is a perspective view of the numbering and 30 name-printing stamp. Fig. 11 is a detail view of the rod and pawl in engagement with the feeding ratchet-wheel adapted to feed the ballot in the forward motion.

My invention comprises a mechanical sys-
35 tem of voting and apparatus therefor where-
by the operation of voting for one or any num-
ber of candidates is greatly simplified and the
evils of repeating and other objectionable fea-
tures overcome and rendered impossible and
40 by which the act of voting is accomplished
with ease and despatch irrespective of the
educational qualifications of the voter.

Referring to the drawings, 2 is the frame
or case of one of my machines, in which are
45 mounted the magazine-roller 3 on shaft 4 and
the ballot-winding wheel 5, provided with hub
6, journaled with friction-springs 7 on shaft
8, having an enlarged middle portion.

The ballot-strip 9 consists of a continuous
50 strip of paper divided by regularly-spaced
central perforations 10 or otherwise into in-
dividual ballot-sections *a*, upon the reverse

side of which are the consecutive-numbering
figures 11. This strip of paper is wound
55 around the roller 3 and led around small roll-
ers 12 13 through orifices in the front wall,
thus exposing upon the outside face of the
machine a section of paper corresponding to
slightly more than the length of one ballot, as
60 shown in Fig. 1. Thence the strip is led un-
der a horizontal guiding-roller 14 and around
the intermittently-actuated positively-driven
feed-roller 15, mounted on shaft 16, and pro-
vided on its periphery with centrally-located
65 projecting pins 17, spaced to correspond to
the distance between the centers of holes 10
in the ballot-strip, into which the pins enter
in the passage of the ballot around the roller,
thus positively feeding the ballot forward.

A push-rod 18 is mounted horizontally in
70 the upper part of the machine, provided with
a pivoted pawl 19, adapted to engage the teeth
of a wheel 20, secured to shaft 16 on the for-
ward stroke, and the motion thus transmitted
75 to the roller 15 is just sufficient to feed the
strip 9 a distance equal to the length of one
ballot.

21 is a bell secured in the top of the case,
adjacent to which is a pivoted knocker 22,
provided with a retracting-spring 23 to throw
80 it forcibly against the bell, and a dog 24, se-
cured to the rod 18, engages the end of the
knocker-arm 25 in the inward travel of rod
18, thus giving a signal for each operation of
85 the rod.

e is a hole in the back of the frame, through
which the ballot-strip may be passed when
voting is finished.

Pivoted to the inside face of the
case at 26 is a bell-crank lever 27, one arm *c*
90 of which projects upwardly and is engaged
by a dog 28, secured to rod 18, and the other
end *d* is attached to a connecting-rod 29,
secured to the end of a pawl-arm 30, having
a pivoted pawl 31, adapted to engage the teeth
95 of a ratchet-wheel 32, (shown in dotted lines,)
secured to the shaft 8, and by this means it
will be seen that at every operation of the
rod 18 the dog 28 will engage the end *c* of the
bell-crank lever 27 in normal position (shown
100 in dotted lines) and will raise the lever to pos-
ition shown in full lines, thus raising the con-
necting-rod 29, and arm 30, and throwing the
shaft 8 around for a portion of a revolution

sufficient to wind up the excess of paper from feed-rollers 15. This travel of the wheel 5 is caused by friction of the shaft 8 and springs 7 in the hub 6, and any excess of travel in 5 the shaft over that in the wheel required to take up the slack is thus permitted, the shaft rotating with the hub.

In the lower front face of the machine is an opening 33, in which is inserted a photograph or picture of the candidate and his name.

In Fig. 10 I have shown a numbering-stamp which is used to stamp upon the ballot the number of the voter and is also provided with 15 a slide 34, bearing the name of each voter. This stamp is retained by the election officer, who inserts the name of each voter and sets it for the next consecutive number, so that when it is given to the voter he merely stamps 20 upon the exposed coupons of each of the machines bearing the names or pictures of the candidates for whom he desires to vote, and retires. A projecting arm 34', having a reciprocating motion with the stamping-wheels, 25 is so designed as to engage and depress the end of the rod 18 when the stamp is used, thus accomplishing the forward feed of the ballot immediately before the stamp comes into contact. In this manner the voter not 30 only feeds the ballot-strip, but stamps his own number and name upon the ballot at one operation.

If preferred, the voter may push in the rod 18 by hand after having stamped his vote, 35 thus effectually concealing it, and for the purpose of so locking the rod as to prevent its withdrawal and operation a second time I have provided at the other end a spring-latch 33, having an under sloping face 33', and immediately back of each rod a distance equal to the stroke of the rod are upright locking-fingers 35, one to each rod, secured to horizontal rock-shafts 36, arranged back of the machines, one shaft to each horizontal row of 40 machines. To the respective ends of these shafts are secured levers 37, and attached to the outer ends of the cranks is a common connecting-rod 38, extending to the bottom and connected to a bell-crank lever 39, having a 45 forwardly-extending rod 40, secured to the lower end of an operating-lever 41, by which the whole series of rock-shafts 36 is operated from one point by the election officer, thus controlling every machine in the booth.

50 It will be seen that a number of the machines are assembled in a booth, one for each candidate, and all candidates of each party are preferably extended in a horizontal row, the vertical rows designating the particular 55 office for which the candidate aspires, as clearly shown in Fig. 6.

In the manner of operation described it will be seen that when the voter enters the booth he is confronted by a series of blank ballots, 60 and in the act of registering his vote each individual ballot is stamped in succession un-

til the entire ticket is voted, each ballot being automatically or independently fed forward as desired and concealed from view, as has been described. In this manner I accomplish the registering of a secret ballot, as the succeeding voter cannot see the previous ballot, nor can any voter cast more than one vote for any one candidate without detection, as his name and number would be duplicated 70 thereby. In Fig. 8 I have shown mechanism by which the feeding of the ballot is accomplished independent of the voter by the return stroke of the rod through the system of levers and locking-fingers already described. 75 The ratchet-wheel 20 is reversed in this case, and the ballot is designed to be fed between two rollers. By this means the voter simply stamps the ballot and depresses the rod and throws the pawl into engagement with the 80 ratchet-wheel 20, the rest of the operation being accomplished by the election officer through the means described. This action assures the secrecy of the previous ballot from the subsequent voter. In the case of a split 85 ticket the voter will use his discretion and choice as to candidates, it being obvious that voting for more than one candidate for the same office will act to nullify the original vote.

Having described my invention, what I 90 claim, and desire to secure by Letters Patent, is—

1. In a voting apparatus, the combination of a case, a magazine-roller mounted therein, a feeding-roller provided with centrally-aligning pins, a winding-roller, a continuous perforated ballot mounted on such rollers and passing through openings in the case to expose a section of the strip, a push-rod provided with a pawl adapted to engage the 100 ratchet-wheel of the feeding-roller and a bell-crank lever having one arm in engagement with a bracket secured to the push-rod and the other pivoted to a lever having a pawl 105 designed to engage the ratchet-wheel of the 110 winding-wheel, substantially as set forth.

2. In a voting apparatus, the combination of a case, a magazine-roller mounted therein, a feeding-roller provided with centrally-aligning pins, a winding-roller, a continuous perforated ballot mounted on such rollers and passing through openings in the case to expose a section of the strip, a push-rod provided with a pawl adapted to engage the 115 ratchet-wheel of the feeding-roller, and a bell 120 mounted in proximity to the push-rod and a knocker pivoted to the case of the apparatus having an arm adapted to be engaged by a projection secured to the push-rod, substantially as set forth.

In testimony whereof I have hereunto set my hand this 27th day of March, 1897.

JAMES B. COREY.
